UNITED STATES PATENT OFFICE.

ROBERT E. CROWLEY, OF GALION, OHIO.

RAILROAD-TICKET.

1,111,298.

Specification of Letters Patent. Patented Sept. 22, 1914.

Application filed December 7, 1909. Serial No. 531,859.

To all whom it may concern:

Be it known that I, ROBERT E. CROWLEY, a citizen of the United States, residing at Galion, in the county of Crawford and State of Ohio, have invented certain new and useful Improvements in Railroad-Tickets, of which the following is a specification.

The present invention relates to railroad tickets, and one of the objects is to provide a single ticket that will not only designate the destination or point to which the purchaser is entitled to ride, but will also identify the portion of the car reserved for the purchaser, this latter identifying portion being detachable, and being so arranged, associated and identified with the body of the ticket that it will constitute more complete protection for the railroad, the conductor and the honest passenger, while providing an effective check against the dishonest passenger.

A still further object is to provide a structure that will prevent stolen tickets or those otherwise wrongfully obtained from being used without the necessity of requiring conductors to remember the numbers and characters of these tickets, as is now the case.

Several embodiments of the invention are illustrated in the accompanying drawings, wherein:—

Figure 1 is a face view of a ticket having a simple form of identification check. Fig. 2 is a face view of a ticket having an identification check that can be used where a change of cars is to be made during a trip. Fig. 3 is a face view of still another embodiment of the invention. Fig. 4 is a similar view showing the two parts of the tickets separated and the blanks not filled in. Fig. 5 is a reverse view of the ticket illustrated in Figs. 3 and 4, showing the form of ticket to be used on excess fare trains.

Similar reference numerals designate corresponding parts in all the figures of the drawings.

Referring first to the embodiment disclosed in Fig. 1, the ticket comprises a main body 3, which may be printed in any well known form, and having connected to one end, one or more detachable checks or coupons 4, which have printed thereon, the points between which the purchaser is entitled to ride upon presentation of the ticket to the conductor. Connected to the opposite end of the body 3 is an identification check 5, so designated at its outer end, as

shown at 6. There is also provided on this check, a blank in which is to be written or printed the destination of the passenger, said blank being so designated at 8. There is also a designated space 9 for the dating stamp, and above the same are a series of blanks 10, 11 and 12 that are suitably designated, and are intended respectively for the reception of the number of the car, the locator of the particular reservation, and the number of the train. Printed across the identification check, is a statement 13 that the said check is not good for passage, and printed on the body 3 is a statement that the ticket is void if the identification check is detached when presented. The various identification checks have printed thereon the name or initials of the railroad, as indicated at 14, and all the checks have corresponding ticket numbers 15 and form numbers 15^a.

The form illustrated in Fig. 2 corresponds in all respects to that disclosed in Fig. 1, with the exception that the identification check is provided with two sets of designated blanks 10, 11 and 12, 10^a, 11^a and 12^a, which are employed where a change of cars is to be made, and the trip is to be extended beyond that for which reservations can be made at the purchasing office, the first set of blanks 10, 11 and 12 being generally designated for the first sleeper, as shown at 16, and the second set being designated the second sleeper, as shown at 16^a. The ticket or Pullman agent will fill in the car number, the location and the number of the train for the first section in order that the passenger may be properly identified upon both trains, and may also have suitable evidence of his right to reservation on the second train. When therefore the change is made, the passenger can go to the office, secure his reservation on the second sleeper, and have the same properly designated on the identification check, or if he has not time for this and can catch his train, by presenting his ticket to the Pullman conductor, he can secure a reservation. Inasmuch as the other features of the ticket are the same as that described in Fig. 1, the same reference numerals have been employed, and it will be evident that the identification check may have as many of these changes indicated thereon, as desired.

The form of ticket illustrated in Figs. 3, 4, and 5, is probably preferred. In this em-

bodiment of the invention, the body of the ticket is designated 17, and the detachable coupons 18 correspond in all respects to those already described. The identification check 19 in this instance, is a separate slip 5 of paper having a tongue 20 detachably secured thereto, which tongue has an adhesive applied to one face, so that it can be secured to the free end of the ticket body 17, and produce the form of ticket above described, 10 but it will be observed that the physical and functional characteristics of the check 19 are the same in all respects as those of the check 5 hereinbefore described in connection 15 with Figs. 1 and 2 of the drawings. This improvement is of particular value to the ticket agents and to prevent the successful use of tickets stolen. In practice the agent keeps the ticket bodies with their detached 20 coupons in a separate place from the identification checks, the latter, for instance, being preserved in a safe. He only places the two together when a ticket is purchased. As a result therefore, if the main portion of 25 the ticket is stolen, it is void without the identification check, and if the identification check is stolen, it is not good for passage. The railroad company is thus better protected, and instead of conductors being required, or at least attempting to remember 30 large numbers of tickets of various types, which a railway company is attempting to prevent being used illegally, the mere presentation of one of these ticket sections, 35 will, in itself, indicate its wrongful use.

At the present time, many railroads run special trains, on which an additional fare is charged, with the condition that if the train is late, a certain amount of that extra 40 fare will be refunded. This heretofore has required an additional double set of tickets and a complicated system requiring much more work on the part of the conductor and the auditors of the various systems. The 45 present ticket can be employed on these excess fare trains without difficulty, by printing on the back of the identification check, a rebate order, as shown in Fig. 5, which can be properly filled in, punched and signed by 50 the conductor, together with a blank receipt to be signed by the passenger when the amount of the excess fare is returned. And in addition, upon the back of the main body of the ticket in all forms thereof, as indicated 55 in Fig. 5 of the drawings may be placed a designated space for the signature of the passenger. This latter can be filled in or not, as the passenger may desire, but it is often of value, for instance, in case of accident, as the conductor will have the names 60 of the passengers, and can thereby find out if any are missing. Furthermore it often occurs that it is desired to deliver messages to passengers on the train, and it is difficult 65 to locate the same. If, however, when the

conductor collects the tickets, he writes upon the backs thereof, the locations of the different passengers directly beneath their signatures, he can then find one to whom a message is addressed without difficulty. In addition to the above, all these forms are of the greatest value, for the identification check when the ticket is collected, is retained by the passenger. He therefore has his reservation certified to, the necessity for 70 a separate receipt, such as is now given, is eliminated, and each passenger has an individual receipt that immediately identifies him and his destination so that he cannot by means of the indefinite receipt now given, 75 ride beyond the point to which he has paid his fare. Furthermore, should a passenger miss his train en route, he can take a subsequent train on his identification check, and the conductor of the succeeding train, upon 80 inspecting said check is able to determine whether or not such is the case, and can get in telegraphic touch with the conductor who holds the ticket to confirm the passenger's 85 right to ride. 90

Another feature of practical importance is employed in connection with the identification check for excess fare tickets. As shown in Fig. 1 of the drawings, the front side of this check is provided with a place 95 for the dating stamp, showing for instance the date of October 15, 1909, as the date of departure of the train on which the ticket is to be honored, and as this particular ticket is indicated as being void one day after 100 date, the excess fare identification check, to be valid must also be provided with a dating space to show what date the amount of refund due the passenger on his excess fare was authorized to be paid by the last conductor, which, in the illustration given 105 would be October 16, 1909. This is shown in Fig. 5 of the drawings, which illustrates the reverse side of the identification check which contains the same spaces and designations in all forms of the invention. 110

Again, in connection with the identification check for all tickets, another detail of practical importance is that of providing the identification checks with punching 115 points or spaces, marked "1, 2, 3 and 4" in the drawings, and which points or spaces are to be punched by the first, second, third and fourth conductors, and so on, to show the points from and to which the ticket has 120 been honored by each conductor. This system acts as a check on the conductors for the coupons taken by each. 125

From the foregoing, it is thought that the construction, operation and many advantages of the herein described invention will be apparent to those skilled in the art, without further description, and it will be understood that various changes in the size, shape, proportion and minor details of construc- 130

tion, may be resorted to without departing from the spirit or sacrificing any of the advantages of the invention.

Having thus fully described my invention, 5 what I claim as new, and desire to secure by Letters Patent, is:—

1. A railroad ticket comprising a body portion bearing a contract form, a detachable destination stub connected to one end 10 of the body portion, a detachable identification check connected with the other end of the body portion and provided on one face with designations giving the date and number of the train ticket and passenger's destination, and having on its other face a rebate form, the said body portion, destination stub, and identification check each bearing identical identification means.
2. A railroad ticket comprising a body 20 portion bearing a contract form and an appropriately designated space for the passenger's signature to be affixed at the time

of purchase, destination stubs connected to one end of the body portion, and an initially unsigned identification check detachably 25 connected with the other end of the body portion and bearing upon one face a rebate form provided with appropriately designated spaces for signatures of the conductor and the passenger to constitute an excess 30 fare rebate check, said identification check being provided on its other face with designations giving the date and number of the train ticket, the passenger's location on the train, and the passenger's destination, the 35 said body portion, destination stubs, and identification check each bearing identical identification means.

In testimony whereof I hereunto affix my signature in the presence of two witnesses.

ROBERT E. CROWLEY.
